US00D950954S

(12) United States Design Patent (10) Patent No.: US D950,954 S
Tran et al. (45) Date of Patent: * May 10, 2022

(54) WALLET

(71) Applicants: Thuan Tran, Santa Clara, CA (US);
Charlie Carroll, Palo Alto, CA (US);
Binh Tran, Santa Clara, CA (US)

(72) Inventors: Thuan Tran, Santa Clara, CA (US);
Charlie Carroll, Palo Alto, CA (US);
Binh Tran, Santa Clara, CA (US)

(73) Assignee: Dango Products, LLC, Portola Valley,
CA (US)

() Term: 15 Years

(21) Appl. No.: 29/729,614

(22) Filed: Mar. 27, 2020

Related U.S. Application Data

(62) Division of application No. 29/679,715, filed on Feb.
8, 2019, now Pat. No. Des. 887,708.

(57) CLAIM

The ornamental design for a wallet, as shown and described.

DESCRIPTION

FIG. 1 shows a front view of the wallet in a closed position. FIG. 2 shows a back view of the wallet in a closed position. FIG. 3 shows an exterior view of the wallet in an open position.

FIG. 4 shows an interior view of the wallet in an open position.

FIG. 5 shows a left side view of the wallet; and, FIG. 6 shows a right side view of the wallet.

The broken line showing of stitching is included for the purpose of illustrating portions of the wallet and forms no part of the claimed design. Any other uniform repeating broken lines being presented depict portions of a wallet in which the claimed design is embodied and form no part of the claimed design.

1 Claim, 6 Drawing Sheets
